(57) **CLAIM**

The ornamental design for a dispenser, as shown and described.

DESCRIPTION

FIG. 1 is a top and right perspective view of a dispenser of the present invention;

FIG. 2 is a right side elevational view of the dispenser of FIG. 1;

FIG. 3 is a top elevational view of the dispenser of FIG. 1;

FIG. 4 is a left side elevational view of the dispenser of FIG. 1;

FIG. 5 is a bottom elevational view of the dispenser of FIG. 1;

FIG. 6 is a front end elevational view of the dispenser of FIG. 1; and,

FIG. 7 is a rear end elevational view of the dispenser of FIG. 1.

The broken lines shown are included for the purpose of illustrating the unclaimed portions of the article and form no part of the claim.

1 Claim, 4 Drawing Sheets
